JOHN B. WORD, OF LATROBE, CALIFORNIA, ASSIGNOR OF ONE-HALF TO WILLIAM F. DEANER, OF AMADOR CITY, CALIFORNIA.

CHAMBERING ATTACHMENT FOR ROCK-DRILLS.

1,061,210.

Specification of Letters Patent.

Patented May 6, 1913.

Application filed April 5, 1912. Serial No. 688,589.

To all whom it may concern:

Be it known that I, JOHN B. WORD, a citizen of the United States, residing at Latrobe, in the county of Eldorado and State 5 of California, have invented certain new and useful Improvements in Chambering Attachments for Rock-Drills, of which the following is a specification.

My invention relates to the class of rock-drills and especially to an attachment therefor for the purpose of which is to enlarge the previously made drill-hole at any point or points desired to provide a distinct chamber or chambers for the reception of the blasting powder.

A further purpose of the attachment is to straighten out what is termed a "fissured" hole; that is, one which, on account of a weakness in the rock, due to a fissure, starts 20 to get out of line or bend.

My invention consists in the novel construction and arrangement of the attachment which I shall now fully describe, by reference to the accompanying drawings, in 25 which—

Figure 1 is an elevation of my attachment, the bit-holder being broken away on one side to show the bits and plunger-head. Fig. 2 is an enlarged detail view of the bit 30 holder, one side and one bit being removed. Fig. 3 is an edge view, enlarged, of the bit holder. Fig. 4 is a broken detail enlarged of a bit holder provided with an arrangement of bits adapted for straightening out 35 a "fissured" hole. Fig. 5 is a horizontal section of the frame bearing for the plunger-sleeve. Fig. 6 is a view showing the application of my attachment to a rock-drill.

The frame of the attachment is composed 40 of two side arms 1 and two front cross pieces 2, the overlapping portions of which are detachably connected by bolts 3, and embody the bearing 4 for the plunger-sleeve 5, said plunger sleeve being rotatably mounted in 45 said bearing 4, and held against lengthwise movement therein by a collar 6 fast upon said sleeve and confined in a slot 7 in the bearing.

Mounted and adapted to be lineally recip-

rocated within the sleeve 5 is the plunger 8, 50 the rear end of which projects from said sleeve a sufficient distance to be inserted in the drill-chuck as I shall presently describe. The head 9 of the plunger is flattened out and presents for its functional portion a 55 double incline-plane or taper, the faces of which are for its best operation made concave as shown. The end of the plunger-sleeve 5 in which the head of the plunger lies and operates is open on each side, as shown 60 at 10, and is somewhat flattened so that while the plunger head can freely move back and forth, it cannot turn on its axis in said sleeve end, from which it follows that any rotary movement given to the plunger will 65 through its head 9 effect the rotary movement of the sleeve 5 also, said sleeve turning in its bearing 4 of the frame. This open-sided end of the plunger-sleeve constitutes what I may term, the bit-holder, and I have 70 herein designated it by 11. It may be of any suitable character for carrying the pivotally connected bits or cutters. In its best construction for chambering work, it consists of the two sides, a cross-pin 12 between 75 their extremities and internal stop-lugs 13 and 13', the relative arrangement and function of which I shall presently describe.

The cutting bits may be of various kinds with respect to their functional surfaces or 80 cutting portions. For example, I have shown one, 14, as having a double cross cutting edge, and another, 15, as having a single longitudinal cutting edge. Two bits like 14 may be used together in the bit-holder; or 85 two like 15; or, as I have here shown, in Fig. 1, for the sake of simplicity, one like 14 may be used on one side and one like 15 on the other side. These arrangements are matters of selection to be made from a 90 knowledge of the character of the rock or the condition of the drill hole, and it follows that other forms of bits may also be used. The bits are made so that they may be readily fitted to and easily removed from 95 the bit-holder. In the present case, each bit is formed with a halved-out ear 16 provided with an open ended slot 17, adapted to fit

over and pivotally engage the cross-pin 12 of the bit-holder 11.

The stop-lugs 13 and 13' inside the bit-head have concave faces as seen in Fig. 2.

5 They are oppositely and reversely arranged with respect to each other, and each is arranged with respect to the cross pin 12 in such manner that it will admit the slotted ear 16 of the bit between its concave face 10 and the cross-pin only when said bit is extended from the head at a relatively great angle, a position it cannot assume when in or under operation in the drill hole. Thus 15 the bit can be readily pivotally fitted in an extended position upon the cross-pin in the first place, and then turned down to lie within the open-sided bit holder in which position and in the slight angular position to which it is thrown outward in actual operation, it cannot disengage itself from the cross-pin, as is plainly evident by reference 20 to Fig. 2. One bit is fitted to the bit-holder on one side, and the other bit is fitted to the other side, and when ready for use they lie 25 beside one another and play in the open sides of the bit-holder. Each bit has a rounded or beveled inner edge 18 for the taper-front of the plunger-head 9 to act against as it enters between the pair of bits.

30 I have herein shown in Fig. 6 a rock-drill with which my attachment is to be used. This is a well known machine, having a body 24 which carries a drill-chuck 25, to which a rapid reciprocating motion is imparted; at the same time an intermittent rotation on its axis being given to it.

19 are the side or tie-rods of the drill machine body which hold the heads together. The forward extremities of these rods 19 40 which are shown clearly in Fig. 1 I modify to the extent of forming them with eyes 20 to receive the pins 21 of the rear ends of the side arms 1 of the frame of my attachment, whereby said frame is thus connected easily 45 to the drill machine-body.

The operation of my attachment is as follows:—When the drill-hole is made and ready for the powder, the drill is removed from the chuck of the machine. Then my 50 attachment is fitted to the ends 19 of the side or tie-rods of the drill machine, and the inner end of the plunger 8 is inserted and clamped in the drill-chuck as shown in Fig. 6. The proper cutting bits being fitted 55 to place in the bit-holder 11, said holder is inserted in the drill hole to the distance desired. Then the drilling machine is started, and the plunger 8 is given a rapid forcible reciprocation, whereby its taper-head 9 acting 60 on and between the beveled inner edges 18 of the cutting bits forces said bits out to cause them to give a series of blows against the walls of the hole. The chuck having its usual intermittent rotation, effects a like

rotation of the plunger 8, and said plunger 65 through its confined head 9 causes the rotation of the plunger-sleeve 5 in its bearing 4, and the consequent rotation of the cutting bits in the bit-holder 11. This operation is continued to the limit of effect of the taper 70 front of the plunger in the bits, and the drill hole is thus chambered or enlarged for the reception of the powder, in some cases, the drill-hole, due to a fissure in the rock or for other causes, bends or deflects from 75 a straight line and must either be abandoned or various expedients resorted to, such as cramming into its inner end foreign substances or bodies, such as nuts or other pieces of metal, which expedients are not always 80 successful. In the case of a "fissured" hole, as it is called, I provide for the use of my attachment, by modifying slightly the bits and their position in the holder, so that said bits may cut right up to the very end or 85 bend of the hole and by a chambering or enlarging effect at that point provide for the straightening of the hole and the continuation of drilling. I show this modification in Fig. 4, wherein in the bit-holder are the 90 cutting bits 22, having their cutting faces at the end of the holder, said bits being pivotally mounted on a pin 23 between their extremities. This arrangement enables the work to be done right up to the end or bend 95 of the hole.

Having thus described my invention what I claim as new and desire to secure by Letters Patent is—

1. A chambering attachment for rock-drills comprising a frame adapted for connection with the rock-drill body; a plunger-sleeve rotatably mounted in said frame; cutting bits movably mounted in the forward end of said plunger-sleeve; a plunger mounted to slide lengthwise in said sleeve and having its rear end projecting therefrom for engagement with the rock-drill chuck; a head on the other end of the plunger adapted by contact with the cutting-bits to 100 effect their operation; and means for locking the plunger sleeve against independent rotation on their axes.

2. A chambering attachment for rock-drills comprising a frame consisting of a 115 pair of side arms having at their rear ends means for detachably connecting them with the rock-drill body, and front cross arms with which the forward ends of the side arms are connected, said cross arms having 120 overlapping ends and a bearing formed between said ends; a plunger-sleeve rotatably mounted in said cross-arm bearing and locked against endwise movement therein by a collar fitted in a slot in said bearing; cutting bits movably mounted in the forward end of said plunger-sleeve; a plunger mounted to slide lengthwise in said sleeve and hav-

ing its rear end projecting therefrom for engagement with the rock-drill chuck; a head on the other end of the plunger adapted by contact with the cutting-bits to effect their operation; and means for locking the plunger and sleeve against independent rotation on their axes.

In testimony whereof I have signed my name to this specification in the presence of two subscribing witnesses.

JOHN B. WORD.
